CLAIM

The ornamental design for a garment steamer, as shown and described.

DESCRIPTION

FIG. 1 is a first perspective view of a garment steamer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The broken lines shown in the drawings depict portions of the garment steamer that form no part of the claim. The dot-dash broken lines indicate enlarged portions of the drawings, and form no part of the claim.
